R. J. O. SIMPSON

WEARING APPAREL

Filed Dec. 19, 1923

Inventor
Robert J. O. Simpson
Attala County
By *Attorney*

UNITED STATES PATENT OFFICE.

ROBERT J. O. SIMPSON, OF ATHOL, MASSACHUSETTS.

WEARING APPAREL.

Application filed December 19, 1923. Serial No. 681,534.

In certain articles of wearing apparel the desirability of means of forming a close, smooth fastening along the line of opening is of paramount importance. Whether this 5 be a matter of needed physical support or of comfort to the wearer or of appearance to others, the closing of such an opening has been long sought and although closely approximated has never been brought to ultimate perfection.

My present invention has been developed as a surgical stocking or bandage or support and as such affords an excellent illustration of its application as well as providing an 15 article of great utility in cases of varicose veins and the like I will discuss it particularly in connection with such an appliance. Throughout the specification and drawings like reference characters are employed to 20 indicate corresponding parts, and in the drawings:

Fig. 1 is a side view of a stocking in accordance with my invention.

Fig. 2 is an enlarged view of a portion of 25 the same.

Fig. 3 is a detailed fragment showing the inside of the opening.

Fig. 4 is a similar fragmentary view with the overlying flaps cut away, and

Fig. 5 is a transverse section on the line 30 5-5, Fig. 1.

The stocking portion 1 is usually especially made so as to carefully fit the member which it is to support or confine. It may, 35 however, be of any construction or material and the seamed and fitted form is merely shown as one most difficult to draw up snugly and smoothly. It will be understood that in a device of this sort it is important 40 that the limb be rather snugly encased without being too tight. In the case of the leg and ankle, it is extremely desirable that the so-called stocking be smooth so that the limb will not appear needlessly ungainly or mis- 45 shapen under the holes.

The stocking member shown is vertically divided as at 2. The edges of this division are formed, as will be seen in Fig. 5, by forming a series of eyelets 3 adjacent the 50 edge of the material on each side and along the line of each side which is to constitute

the edge 2. In finishing, the edge portion 1¹ of the stocking is folded back so that the eyelets 3 are left on the edge. This portion is then stitched down as at 4 and the edges 55 preferably covered by a stitched strip 5 which binds the edge and strengthens it. The stocking is laced by a pair of lacings L. These are worked through by curved needles N by passing the needle from one eyelet to 60 the next on one edge and then crossing to the opposite eyelet passing to the next on that edge and then returning to the opposite eyelet on the first edge and so on. The edges are therefore drawn close together 65 with the eyelets in registry and with the lacings crossing each other at each opposed pair of eyelets. On each side between the eyelets there is a length of lacing laid within and covered by the overturned seam. After 70 the stocking is once laced upon the leg it may be removed at any time by loosening one end of the lacing, as for example at the upper end. For this purpose the lacings L are preferably provided long enough so that 75 the lacing can be travelled down and the opening spread for the full length without the necessity of again threading in the lacings by the use of a needle.

While my invention is of great importance 80 in the form shown and described, it will be understood that it has other applications and that a device such as is herein shown or otherwise may be variously modified all without departing from the spirit of my invention if within the limits of the appended 85 claim.

What I therefore claim and desire to secure by Letters Patent is:

A surgical stocking consisting of a shaped 90 length of sheet material longitudinally divided from end to end thereof to provide a pair of abutment edges which are overfolded upon themselves to form with the underlying portions of the stocking a pair 95 of longitudinally extending channels, said channels being pierced at said overfolded edges by oppositely disposed eyelets arranged in spaced relation longitudinally of the stocking, and a lacing for each channel, 100 each lacing being passed from one eyelet to the next eyelet on one edge of the stocking

and then crossed to the opposite eyelet on the opposing edge of the stocking, and from said opposite eyelet being carried to the eyelet next above on said opposing edge and 5 being finally returned to the opposite eyelet on the first-named edge, whereby when the edges are drawn together the lacings cross

each other at opposite eyelets and those portions of the lacings between two spaced pairs of opposite eyelets are disposed within and 10 covered by the seams formed by said channels.

In testimony whereof I affix my signature.

ROBERT J. O. SIMPSON.
